LIFTING DEVICE FOR HANDLING CONVECTION SPACER DISKS

Max R. Heppenstall, Pittsburgh, Pa., assignor to Heppenstall Company, Pittsburgh, Pa., a corporation of Pennsylvania

Application December 18, 1953, Serial No. 399,073

16 Claims. (Cl. 294—94)

The present invention relates to a lifting device for handling convection spacer discs.

In the steel industry sheet strip steel is normally rolled into coils at the rolling mill. For purposes of heat treatment, these coils are placed one above the other in stacks, and a disc called a convection spacer disc is placed between each coil of strip steel in the stack. These convection spacer discs are provided with radially extending ribs which permit movement of air through the discs to transfer heat by convection.

In building up a stack it is necessary to put in place a coil of strip, place a spacer disc on top of the coil, place a coil of strip on top of the spacer disc, and so on until the stack is built up to the desired height. To facilitate this building up of a stack the lifting device of the invention is provided with controls which permit it to drop off a single spacer disc from the bottom of a pile of spacer discs carried by the lifting device.

In taking down a stack, the device is provided with controls which permit it to pick up a single disc and add it to the bottom of a pile of spacer discs carried by the lifting device.

The controls of the device may also be set so as to deposit the entire pile of spacer discs that were being carried by the lifting device.

These and other objects of the invention will become apparent as the description proceeds.

In the drawings:

Fig. 1 is a side elevation on line I—I of Fig. 2 of the lifting device of the invention being used to deposit a convection spacer disc on a coil of rolled strip steel.

Fig. 2 is a top plan view of the device of Fig. 1, parts being broken away to show the coil of steel strip.

Fig. 3 is a detailed diagrammatic view illustrating the operation of the device in depositing a single spacer disc on a coil.

Figs. 4 and 5 are views similar to Fig. 3 but showing the parts in different operating positions.

Figs. 6 and 7 are views quite similar to Fig. 3 but showing different types of operation of the lifting device.

Referring to the drawings more particularly, the reference character 10 represents a coil of steel strip and 11 are convection spacer discs provided with radially extending ribs 12. (See Figs. 1 and 2.)

The lifting device includes a head 13 from which extend downwardly plates 14 which form channels to receive the operating members. A lifting link 15 attached to the head 13 provides means by which the lifting device may be attached to a crane or other carrying mechanism. The construction of the head 13 will not be given in detail since various mechanical arrangements can be used for this part of the structure.

A pair of the plates 14 are spaced parallel to each other to form a channel as indicated in Fig. 2, and there are preferably three of these channels spaced symmetrically about the circumference of the lifting device. The plates 14 are preferably welded or otherwise secured together and to the head 13, so as to provide a strong, unitary body. The downward extensions formed by the plates 14 may be considered a mandrel, which is adapted to extend into the openings in the convection spacer discs and also into the central openings in the coils of sheet steel.

At the lower end of each of the channels formed by the plates 14, a guide shoe 16 is pivoted on a pin 17. An operating link 18 has one end pivoted to an inner extension of the guide shoe, and its other end, to an operating plate 19 carried at the lower end of operating rod 20. A stop pin 21 limits outward movement of the guide shoe. Below the guide shoes 16 the plates 14 are tapered inwardly so as to form a blunt tapered point for the mandrel.

2

The function of the guide shoes 16 is to guide and accurately center the mandrel within the opening in the convection discs or the coil of strip steel. Thus when the mandrel is lowered into the annular opening in a stack of convection spaced discs or into the opening in a coil of strip steel, the tapered surfaces 22 provide a rough guide to guide the mandrel into the opening and then the guide shoes 16, which are then in their outwardly extended position, engage the edge of the opening and serve to accurately center the mandrel within the opening so as to permit the operating parts to properly engage the convection spacer disc, as will subsequently be explained.

In order to permit the lifting device to engage and lift the convection spacer discs, each of the channels provided by members 14 is furnished with a latching dog 23 swinging on a pivot pin 24. The latching dogs are controlled by operating mechanism which permits them to raise an entire stack of convection spacer discs or to deposit the disc at the bottom of the stack on top of a coil 10 of sheet steel. The mechanism for operating these latching dogs will now be described in detail.

Each latching dog is in the form of an L-shaped bell crank lever having a horizontal leg 25 and a vertical leg 26. Extending outwardly from the vertical leg is a lip 27 which is adapted to engage under the convection spacing disc. The vertical leg also carries a vertically extending catch 28 which engages stop pin 29 to limit outward movement of the latching dog.

The operating cam for the latching dog is in the shape of an L-shaped lever which is pivoted on the pivot pin 29 and has a horizontal leg 30 and a vertical leg 31. The outer surface of the vertical leg 31 is curved for a purpose presently to be described.

While only one latching dog 23 and its operating parts has been mentioned in order to simplify the description, it should be understood that there is a latching dog 23 mounted in each of the channels formed by the plates 14.

A yieldable operating connection is provided between the horizontal leg 30 of the operating cam and the horizontal leg 25 of the latching dog. This yielding connection includes a yoke 32 (Fig. 3) which is connected to horizontal leg 30 by the pivot pin 33. A bolt 34 extends through the bottom of the yoke and is pivoted to the arm 25 by pivot pin 35. A compression spring 36 is mounted between the head of the bolt and the bottom of the yoke.

Mechanism is provided to control the latching dog. For this purpose, an inner sleeve 37 surrounds the operating rod 20 and carries a detent 38. The upper end of the inner sleeve 37 carries an operating member 39 which is pivoted at 40 to a lever arm 41. The operation and control of lever arm 41 will be described shortly.

The upper end of the outer sleeve 42 carries an operating yoke 44 which has a pivotal connection 45 with the lever arm 46. The lower end of sleeve 42 carries a detent 43, which controls the operating cam. The operation and control of lever arm 46 will be described shortly.

The operative positions of the inner sleeve 37 and outer sleeve 42 are determined by a cam 47 which is rotatable on a shaft 48 mounted on the head 13 and rotatable by means of a crank handle 49. (See Figs. 1 and 2.) While in Fig. 3 only one lever arm 41 shows, there are actually two levers 41, as may be seen from Fig. 2. A roller 50 rotatably mounted between the lever arms 41 at one end is adapted to cooperate with the cam 47, and the opposite ends of the lever arms 41 are pivoted at 51 on the head 13.

Similarly, a roller 52 is mounted between the lever arms 46 for cooperation with the cam 47. The opposite ends of the lever arms 46 carry the pivot 45 which cooperates with the operating yoke 44. The lever arms 46 are pivoted at a point intermediate their length on pivot 53 mounted on the head 13.

The kidney-shaped cam 47 is provided with dwells which are adapted to receive the rollers 50 and 52. The different positions of this cam permit different operations of the lifting device as follows:

Position A (deposit one at a time)

When the selector cam 47 is in the position illustrated in Figs. 1 to 5, inclusive (which may be called position A),

the parts are so disposed that the lifting device will deposit the bottom one of a pile of convection spacer discs being carried by the lifting device. The operation of the lifting device in depositing the bottom disc from the pile carried by the lifting device, is as follows:

In this position the guide shoes 16 are in their outwardly extending positions. This is due to the fact that the operating rod 20 is not being lifted upwardly by lever 46 and hence the downward weight of rod 20 and related parts pulls downwardly on the operating link 18 which in turn pushes the shoe 16 to its outer extended position. These shoes will, therefore, serve to guide and accurately center the lifting device as it moves downwardly in the cylindrical opening inside the coil 10 of sheet steel.

In the position illustrated in Figs. 1 and 3, the latching dogs 23 are in their outer position with lips 27 engaged under the lowermost convection spacer disc. While the pile of spacer discs is being carried and transported by the lifting device, the weight of the stack of discs on the lips 27 holds the latching dogs in their outer position. However, as the handling device is lowered into the cylindrical opening of the coil 10 of strip steel, the lower spacing disc engages the upper surface of the coil 10 and the handling device continues its downward movement, thereby relieving the lifting dogs of the weight of the pile of spacer discs. When the lifting dogs 23 are relieved of this weight they immediately snap inwardly to the position illustrated in Fig. 4. At the same time the vertical leg 31 of the operating cam moves outwardly to the position of Fig. 4.

The movement just described of the latching dogs 23 and operating cams is due to the fact that the major portion of the mass of the latching dogs 23 and of the operating cams is inwardly (that is to the right side as viewed in Fig. 3) from the pivots 23 and 29, so that these parts are biased by gravity to the position of Fig. 4.

The latching dogs 23 are now retracted so that the entire lifting device can be moved upwardly from the position of Fig. 4 to the position of Fig. 5. During this movement the latching dogs by-pass the bottom spacer disc. When the parts reach the position of Fig. 5, the outer curved or cam surface of the vertical leg 31 of the operating cam engages the inner periphery of the lowermost spacing disc. The inner edge of the spacing disc therefore presses inwardly on the vertical leg 31 of the operating cam, thereby causing the lip 27 of the latching dog to move outwardly and engage under the next to the bottom of the convection spacer discs. This outward movement of the lip 27 is due to the fact that upward movement of the horizontal arm 30 of the operating cam pulls upwardly on the yielding connection, which includes the bolt 34, thus pulling upwardly on the horizontal arm 35 of the latching dog and causing the vertical arm to move outwardly.

In this way the latching dogs are moved past the lowermost of the spacer discs but are caused to engage under the next-to-the-bottom of the spacer discs, thereby lifting the entire pile except for the bottom spacer disc which is left in place on top of the coil 10 of sheet steel.

In normal operation the pile of spacer discs is now moved by the lifting device out of the way and a second coil 10 is placed on top of the spacer disc which has just been deposited. The operation is then repeated so that a single spacing disc is deposited between each pair of coils 10, to build up the stack of coils 10 to the desired height.

As the lifting device is moved upwardly past the disc that has just been deposited on a coil 10, the inner periphery of the disc will engage the upper surface of the guide shoes 16 and this pressure is sufficient to move the guide shoes downwardly and inwardly to permit them to move past the disc. This is due to the fact that the distance from the pivot 17 to the outer edge of the guide shoe provides a relatively long lever arm and thus provides sufficient leverage to pull upwardly on the links 18 and permit the inward and downward swinging of the guide shoe 16.

Position B of cam 47 (pick up one or more)

Fig. 6 illustrates position B of the cam 47 in which the parts are set so as to permit the device to pick up one or more of the convection spacer discs.

In moving cam 47 from the position of Fig. 3 to the position of Fig. 6, the shaft 48 on which cam 47 is mounted has been rotated counterclockwise for 90° to

bring the long axis of the kidney-shaped cam 47 to the vertical position. During this movement of the cam, there is no movement of lever arm 41 because the roller 50 on the outer end of arm 41 is kept at the same distance from the axis of shaft 48. The outer end of shaft 46, however, is moved downwardly because the roller 52 is now at a greater distance from the axis of shaft 48 than it was in Fig. 3.

This downward movement of roller 52 causes levers 46 to swing about the pivot 53, thus pushing upwardly on the yoke 44, which carries with it the outer sleeve 42 and the detent 43. The detent 43 is now engaged under the horizontal leg 30 of the operating cam, thus locking the operating cam in its inward or retracted position.

With the parts in this position, the lip 27 of the latching dog is in its outer or extended position. As the lifting device is lowered down through a stack of convection discs, the latching dog is pressed inwardly by its lower inclined surface engaging with the inner edge of a disc, the inward movement of the latching dog being permitted by the yielding of spring 36. As it passes each disc, the lip 27 snaps outwardly so that after it has passed the lowermost of the spacing discs it is in a position to lift the entire stack of discs. Hence, in this position the lifting device can pick up the discs one at a time, as the stack of coils is being taken down, or it can pick up a pile of discs.

When the cam 47 was moved to the position of Fig. 6, it also caused the guide shoe 16 to move to its inward retracted position. This movement is caused by upward movement of the operating yoke 44 pushing upwardly on the lower end of vertical arm 55 which is attached to the upper end of the operating rod 20. The corresponding upward movement of operating plate 19 pushes upwardly on the inner arm of guide shoe 16 causing the main body of the guide shoe to swing from the position of Fig. 3 to the position of Fig. 6.

Position C of cam 47 (full discharge position)

Fig. 7 illustrates the position C of the cam 47 in which the parts are so set that when the weight of the load of convection spacer discs, whether it be one disc or a plurality of discs, is deposited on top of a coil of sheet steel, thus relieving the latching dogs of the weight of the load, these latching dogs move inwardly permitting the lifting device to be entirely disengaged and raised upwardly through the convection spacer discs.

It will be noted that in moving from the position of Fig. 6 to the position of Fig. 7, the shaft 48 has been rotated counterclockwise 90°. During this movement there is no change in the position of roller 52 since the cam maintains it at the same distance from the axis of shaft 48. However, the dwell of cam 47 that is now in position to receive the roller 50 is closer to the axis 48 than it was in Fig. 6. Normally the cam is moved to the position of Fig. 7 while the lifting device is carrying a stack of spacer discs with the weight of the discs carried by the latching dogs 27, as shown in Fig. 6. While the weight of the stack of discs is on the lips 27 of the latching dogs, there can be no downward movement of roller 50 because the horizontal arm 25 of the latching dog is engaged under the operating plate 38 attached to sleeve 37. Hence, sleeve 37 and the parts connected with it are held in the same position they occupy in Fig. 6.

However, as soon as the weight of the stack of spacer discs is lifted from the dogs 27 the weight of sleeve 37 and attached parts presses downwardly on the inner leg 25 of the latching dog, thereby swinging inwardly the lip 27 of the latching dog to its retracted position of Fig. 7. Position C of cam 47 permits this downward movement of the outer sleeve 37, since the dwell for receiving the roller 50 is now closer to the axis 48 than it was in Fig. 6.

When the parts are in the position of Fig. 7, the guide shoe 16 is held in its inward or retracted position because the lever arm 46 is in the same position it was in Fig. 6.

Conclusion

It will be clear from the above description that the lifting device of the present invention provides a convenient means for handling convection spacer discs in building up, or taking down, a stack of coils of strip steel.

According to the provisions of the patent statutes, I have explained the principle of my invention and have

illustrated and described what I now consider to represent its best embodiment. However, I desire to have it understood that, within the scope of the appended claims, the invention may be practiced otherwise than as specifically illustrated and described.

I claim:

1. A lifting device for handling discs which comprises: a head provided with a lifting connection, a mandrel depending from the head and provided with a plurality of channels, each of the channels having pivoted therein a latching dog movable from an outer position in which it is adapted to engage under a disc, to an inner inoperative position in which it will pass through the opening in a disc, an operating cam for each latching dog, the operating cam being pivoted in the channel and being connected to the latching dog, a guide shoe pivoted in each of the channels, a manually-operated cam mounted on the head, and means controlled by the manually-operated cam for controlling movement of the latching dogs, the operating cams and the guide shoes.

2. A lifting device for handling discs which comprises: a mandrel for insertion in the cylindrical opening in a coil of strip material, a plurality of latching dogs pivoted on the mandrel, each latching dog being movable from an outer position in which it is adapted to engage under a disc, to an inner inoperative position in which it will pass through the opening in a disc, an operating cam for each latching dog, the operating cam being pivoted on the mandrel and having a vertical leg adapted to engage the inner periphery of a disc, and a horizontal leg connected to the latching dog, the operating cam being connected to cause the latching dog to move outwardly when the vertical leg of the operating cam engages the inner periphery of a disc.

3. A device as recited in claim 2 in which a detent is provided to hold the latching dogs in their inner retracted position, and manual control means is connected to the detent to control the detent.

4. A device as recited in claim 2 in which a detent is provided to hold the operating cams in their inner inoperative position, and manual control means is connected to the detent to control the detent.

5. A device as recited in claim 2 in which a detent is provided to hold the latching dogs in their inner retracted position, and a detent is provided to hold the operating cams in their inner inoperative position, and manual control means connected to the detents and movable to control both of said detents.

6. A lifting device for handling discs which comprises: a mandrel for insertion in the cylindrical opening in a coil of strip material, a plurality of latching dogs pivoted on the mandrel, each latching dog being movable from an outer position in which it is adapted to engage under a disc, to an inner inoperative position in which it will pass through the opening in a disc, an operating cam for each latching dog, the operating cam being pivoted on the mandrel and having a vertical leg adapted to engage the inner periphery of a disc, and a horizontal leg connected to the latching dog, each operating cam being movable from an outer position in which it operates the latching dog when contacted by a disc, to an inner position in which it is inoperative.

7. A device as recited in claim 6 in which a detent is provided to hold the latching dogs in their inner retracted position, and manual control means is connected to the detent to control the detent.

8. A device as recited in claim 6 in which a detent is provided to hold the operating cams in their inner inoperative position, and manual control means is connected to the detent to control the detent.

9. A device as recited in claim 6 in which a detent is provided to hold the latching dogs in their inner retracted position, and a detent is provided to hold the operating cams in their inner inoperative position, and manual control means connected to the detents and movable to control both of said detents.

10. A lifting device for handling discs which comprises: a mandrel for insertion in an opening in a disc, a plurality of latching dogs pivoted on the mandrel, each latching dog being in the form of an L-shaped lever with a vertical leg which extends upwardly from the pivot and a horizontal leg which projects inwardly from the pivot, the vertical leg having at its upper end a lip which projects outwardly to engage under a disc, each latching dog being swingable from an outer position in which it is adapted

to engage under a disc, to an inner retracted position in which it will pass through an opening in a disc, an operating cam for each latching dog, each operating cam being in the form of an L-shaped lever with a vertical leg projecting downwardly from the pivot, and a horizontal leg projecting inwardly from the pivot, the horizontal leg of the operating cam being connected to the horizontal leg of the latching dog, each operating cam being swingable from an outer position in which it operates to move the latching dog outwardly when contacted by a disc, to an inner position in which it is inoperative.

11. A device as recited in claim 10 in which a detent is provided to hold the latching dogs in their inner retracted position, and manual control means to control the detent.

12. A device as recited in claim 10 in which a detent is provided to hold the operating cams in their inner inoperative position, and manual control means movable to control the detent.

13. A device as recited in claim 10 in which a detent is provided to hold the latching dogs in their inner retracted position, and a detent is provided to hold the operating cams in their inner inoperative position, and manual control means movable to control both of said detents.

14. A lifting device for handling discs which comprises: a mandrel for insertion in an opening in a disc, a plurality of latching dogs pivoted on the mandrel, each latching dog being in the form of an L-shaped lever with a vertical leg which extends upwardly from the pivot and a horizontal leg which projects inwardly from the pivot, the vertical leg having at its upper end a lip which projects outwardly to engage under a disc, each latching dog being swingable from an outer position in which it is adapted to engage under a disc, to an inner retracted position in

which it will pass through an opening in a disc, an operating cam for each latching dog, each operating cam being in the form of an L-shaped lever with a vertical leg projecting downwardly from the pivot, and a horizontal leg projecting inwardly from the pivot, the horizontal leg of the operating cam being connected to the horizontal leg of the latching dog, each operating cam being swingable from an outer position in which it operates the latching dog when contacted by a disc, to an inner position in which it is inoperative, and a spring-biased connection between the latching dog and the operating cam.

15. A lifting device for handling discs which comprises: a mandrel for insertion in an opening in a disc, a plurality of latching dogs pivoted on the mandrel, each latching dog being movable from an outer position in which it is adapted to engage under a disc, to an inner inoperative position in which it will pass through the opening in a disc, a plurality of guide shoes pivoted on the mandrel, each guide shoe being movable from an outer position in which it is adapted to guide and center the mandrel in an opening, to an inner inoperative position, and a manually movable control cam controlling the latching dogs and the guide shoes.

16. A lifting device for handling discs which comprises: a mandrel for insertion in the cylindrical opening in a coil of strip material, a plurality of latching dogs pivoted on the mandrel, each latching dog having an outwardly extending lip with a flat upper surface adapted to engage under a disc, for carrying the disc, and with an inclined lower surface which is adapted to engage the inner edge of a disc to move the latching dog inwardly, an operating cam for each latching dog, each operating cam being in the form of an L-shaped lever with a vertical leg projecting downwardly from the pivot and having an outer curved cam surface, and a horizontal leg projecting inwardly from the pivot, the horizontal leg being connected

70 to the latching dog by a yielding connection, the operating cam being swingable from an outer position in which its cam surface may be contacted by a disc to cause outward movement of the latching dog, to an inner position in which the yielding connection permits the lip of the latching dog to move inwardly when a disc presses against the inclined lower surface of the lip.
